CLAIM

The ornamental design for a sensor cover, as shown and described.

DESCRIPTION

FIG. 1 is a top right front perspective view of a sensor cover. FIG. 2 is a front elevation view of the sensor cover of FIG. 1.

FIG. 3 is a rear elevation view of the sensor cover of FIG. 1. FIG. 4 is a left side elevation view of the sensor cover of FIG. 1.

FIG. 5 is a right side elevation view of the sensor cover of FIG. 1. FIG. 6 is a top plan view of the sensor cover of FIG. 1. FIG. 7 is a bottom plan view of the sensor cover of FIG. 1. FIG. 8 is a perspective view of the sensor cover of FIG. 1; and,

FIG. 9 is an enlarged perspective view of the sensor cover of FIG. 1.

The broken lines shown in the drawings indicate unclaimed features and form no part of the claimed design.

1 Claim, 6 Drawing Sheets
